PAGE 2

Fig. 2

FIG. 3

FIG. 1 is a perspective side view upon one lengthwise side of the toy roller coaster trackway showing my design;

FIG. 2 is a perspective side view upon the opposite lengthwise side of the toy roller coaster trackway of FIG. 1; and

FIG. 3 is a plan view of FIG. 1.

I claim:

The ornamental design for a toy roller coaster trackway, as shown.
